UNITED STATES PATENT OFFICE

1,940,049

MACHINE HAVING PISTONS AND CYLINDERS ARRANGED AROUND A CIRCUMFERENCE

Jean Dap, Puteaux, France, assignor to Dap-Motor Patent Gesellschaft m. b. H., Cologne-Holweide, Germany, a company of Germany

Application September 18, 1929, Serial No. 393,486, and in Germany October 3, 1928

5 Claims. (Cl. 123—43)

I have filed applications in Germany dated 3rd October, 1928 and France dated 29th January, 1929.

The present invention relates to a reversible machine in which two members or two groups of members (the cylinder or cylinders and the piston or pistons) are disposed around a circumference, in which machine the cylinders for example turn at a uniform speed, the pistons executing 5 on the circumference on which they are located an alternative movement such as to retard them relatively to the cylinders (during the motor cycle for example) and to subsequently to again catch the said cylinders and so on.

10 It has been observed that in a machine of this type the best efficiency is obtained when the mechanism which actuates the members executing an intermittent movement does not partake directly or positively of the transmission of work.

15 Moreover, for obtaining an efficient operation of such a machine it is necessary for the member which effects the intermittent movement, the piston for example, to move in such a manner that, for a high speed of rotation of the apparatus, the 20 variations in speed of the said member do not give rise to an inadmissible force of inertia and that the said member is locked in two positions during the expansion in the cylinder, this locking being effected automatically by means of a 25 locking mechanism.

For obtaining these results and in accordance with the present invention there is used for actuating the intermittently moving members a mechanism consisting of a bent lever serving as a connection between the member rotating uniformly and the intermittently moving member. One end of this lever is in a curved groove provided on the framework of the machine in such a manner that the intermittently moving member is actuated 30 with progressive variations of speed.

This lever of which the bent portion is mounted in such a manner that it can pivot on the member rotating at a uniform speed, is connected at its other end to the intermittently moving member 35 by means of a device for compensating length, for example a slide. Moreover and also in accordance with the invention the actuating mechanism above referred to its withdrawn from the action of the driving force exerted on the immovable piston during the driving period by means of a locking mechanism which automatically locks the 40 piston during the period of time in question, which locking mechanism is actuated by the cylinder subjected to a uniform movement of rotation.

In the accompanying drawings there are illustrated diagrammatically and solely by way of example a few forms of construction of a machine according to the present invention.

Figure 1 is a longitudinal section on the line I—I of Figure 2 of a machine provided with two cylinders and two pistons mounted diametrically, which machine may for example be a two-stroke cycle internal combustion engine.

Figure 2 is a section on the line II—II of Figure 1.

Figure 3 is a diagram of the operation of the machine.

Figure 4 is a simplified diagram of the device illustrated in Figure 1, which diagram shows the efforts which are exerted by the various members.

Figure 5 is a diagram of a machine with corresponding double pistons and cylinders opposed in tandem on a circumference.

Figure 6 is a diagram of operation showing the 75 reversibility of the direction of operation of the machine in Figure 5.

Figure 7 is a section on the line VII—VII of Figure 8 and shows a form of construction of the device shown diagrammatically in Figure 5.

Figure 8 is a section on the line VIII—VIII of Figure 7 and shows an example of construction of the locking device.

For the greater clearness there are not shown in the drawings the devices for cooling, ignition, 85 actuation of the valves, and so forth, these devices being adapted to be of any suitable type and arranged in any suitable manner. For the same reasons the device for lubricating the machine is not illustrated, this device may be of any suitable 90 character, for example a bath of oil disposed in the framework forming the crank case, the rotation of the members ensuring the lubrication thereof themselves. It will also be understood that any suitable filtering, cooling and heating 95 device for the lubricant may be provided without departing from the scope of the invention.

In Figures 1 and 2 there is illustrated diagrammatically a form of construction of the machine in which A indicates the cylinders disposed around a circumference, which cylinders form a block with a fly wheel hinged at the points B to the members C which connect each of the cylinders A to one of the pistons D.

The block of cylinders A is secured to a hollow driving shaft E arranged so as to permit of the admission of the driving fluid. The supply and outflow of the cooling fluid as also the exhaust of the gases may be effected in a similar manner.

Each of the pistons D, mounted loosely on the 110

driving shaft E, carries at F a trunnion serving as a guide for a slide G of the member C. Each of the members C effecting the connection between the members A and D is in the form of a bent lever, in the example illustrated in the drawings, of which the bent portion is hinged at B and of which one arm is hinged at F by means of the slide G above referred to. The free end, L of the lever C carries rollers M and N which respectively roll on the outer portion O and on the inner portion P of a curved roller track having such an outline that the piston D is stopped during the driving period during which period the corresponding cylinder A moves at a uniform speed in the direction of the arrow.

Each of the pistons D may also be blocked during the driving period by means of a locking device independent of the lever C. This locking device, indicated simply by H in Figures 3, 4 and 5, is carried by the framework K of the machine. It may be constructed by means of a pin, key, wedge, an automatic pawl and may be actuated in any suitable manner. A form of construction of the locking device will be described hereinafter.

In Figure 3 are shown the different positions occupied by the members of the machine. According to this figure the point B (which for example is a point of a fly wheel secured to the cylinder A) traverses, during the driving period of the cylinder, the path B0—B8 and the point L of the lever C, during the same period, moves from L0 to L8. During the same period the pivot point F of the lever C is at the stop in the position F0—F8. At this moment and under the influence of the curve OP the piston D moves at a speed which accelerates, passes a maximum and is reduced so as to again acquire the value zero.

The above movement of the point F moves it from the position F0—FS to the position F16. During this latter movement the point B traverses the path B8—B16 and the point L passes from the position L8 to the position L16. This is repeated as many times as desired during a revolution of the machine. There may be any suitable number of cycles, but it will be understood that this is always a whole number.

It may be mentioned (see Figure 4) that the deleterious forces (efforts during the driving period) are not forces directed in an opposite direction to the movement of the cylinder, but simple retarding forces which are relatively small and due to friction.

It may also be mentioned that by the provision of the member C with an independent locking device, hereinafter described, in other words causing the push p of the piston to be supported directly (for example at the point H in Figure 3 as indicated above) no longer by the member C, but by a member fixed to the framework of the machine, the retarding forces referred to above are absorbed to a considerable extent. The lever C driven by B can then oscillate freely having regard to the fact that it no longer supports directly the shock due for example to the explosion and consequently the general efficiency of the apparatus is improved.

The diagram in Figure 4 illustrates diagrammatically a machine in which there are diagrammatically arranged two units A, C, D and of which one of the cylinders may be regarded as the driving cylinder, the other being the compression cylinder. When the two cylinders are driving cylinders a portion of the internal forces on the members is balanced.

The machine described may, subject to the modifications illustrated in Figures 5 and 7, be reversible in rotation. In fact if it is considered that the cylinder A (acting as a driving cylinder) causes the shaft E to rotate in a clockwise direction and that the cylinder Q is a compression cylinder (two-stroke cycle) it will be seen that by reversing, by any suitable method, the actions of the admission and exhaust members for the gases (after slowing down the machine) the cylinder Q may become the driving cylinder and the cylinder A the compression cylinder. The shaft E then turns in an anticlockwise direction.

Figure 6 shows the different positions occupied successively by the members of the device shown diagrammatically in Figure 5.

Figure 7 shows diagrammatically the manner in which the device illustrated diagrammatically in Figure 5 may be carried out in practice. In Figure 7 there are used the same references as in the preceding figures for indicating similar members.

The locking device which may be constructed as shown in Figure 8 corresponds with the locking device indicated by H in Figures 3, 4, 5 and 6. This locking device is provided for example with a pin R sliding in a boss S carried by the framework K. This pin may enter a recess T provided in a boss U formed on the pistons D. At the opposite end of the pin which enters the recess T the said pin is hinged to a lever V pivoted at W and of which the end X engages with a groove Y of a cam Z keyed to the driving shaft E.

The shape of the groove Y of the cam Z is such that it produces, by a suitable oscillation of the lever V, the to and fro movement of the pin R which, by engaging the boss U of a piston, locks the latter in a suitable position (driving period) which position corresponds to that for example indicated by F0—F8 in Figures 3 and 6.

I claim:

1. In combination, a plurality of pistons rigidly connected together, a cylinder-block having toroidal bores formed therein coacting with said pistons, said cylinder-block including a plurality of cylinder heads positioned to coact with said pistons to form a plurality of combustion chambers, a fixed frame, a cam supported on said frame, said cam having a groove positioned exteriorly with relation to said pistons, and crank-levers pivotally mounted on said cylinder-block, each of said crank-levers having one extremity in pivotal engagement with a piston and the other connected in guiding relation to said cam, the portion of said crank levers connected in guiding relation to said cam and in pivotal engagement with the piston forming an angle greater than 180° on the sides thereof facing same cam.

2. A structure as defined in claim 1 in combination with means operative to intermittently block said pistons in position relatively to said fixed frame.

3. A structure as defined in claim 1 in combination with cam controlled means operative to intermittently block said pistons in position relatively to said fixed frame.

4. A structure as defined in claim 1 in combination with a reciprocable pin adapted to engage with one of said pistons to intermittently lock the latter in position, and means for reciprocating said pin.

5. A structure as defined in claim 1 in combination with a reciprocable pin, and cam actuated means for reciprocating said pin so as to move the latter intermittently into engagement with one of said pistons.
